UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

PRODUCTION AND TRANSMISSION OF MODULATED WAVES.

Application filed December 27, 1921. Serial No. 525,012.

The present invention relates to the production of modulated waves by commutation of the signaling currents, and comprises both means and method therefor.

- 5 The invention further relates to the transmission and reception of the modulated waves so produced, including method and means of purifying the waves for transmission and reception, controlling transmission 10 of different waves or different portions of the same wave selectively, and accomplishing other effects such as will appear from the more detailed description to follow.

If alternating current is produced by commutating a direct current, it is known that the amplitude of the alternating current varies according to the magnitude or strength of the direct current. From a varying direct current an alternating current of varying amplitude can therefore be produced. When the direct current is a signaling current, a signal modulated wave may be produced by commutation. The signaling current need not be a varying direct current, however, for if it be an alternating current, the resulting high frequency wave produced by commutation of the signal current will be substantially a pure modulated wave as explained later. The commutator 30 may, therefore, be used as a modulator in carrier current transmission, and this type of modulator possesses some distinct advantages over types of modulators heretofore used, such as the vacuum tube. These advantages will be pointed out later on in the detailed description.

To reconver the alternating current wave into current of the signal frequency any suitable type of detector or rectifier may be used, but since a commutator acts as a rectifier of alternating current if run in synchronism with the current alternations, a commutator can be used for detecting the received wave. Further, the same commutator used to produce an outgoing modulated wave may be used to rectify the incoming waves. A channel may terminate at each end in a commutator which serves both to modulate and detect, these commutators being run in synchronism with each other in any suitable manner. For multiplex operation different simultaneous message currents are commutated at different rates and filters are used to separate the current com-

ponents of the different frequencies employed by the respective channels.

For a better understanding of the various features of the invention and its exact nature and objects, the following detailed description and the appended claims may be consulted, reference being had to the accompanying drawings in which Figs. 1 and 2 show curves illustrative of the manner of operation of a commutator in modulating and detecting; Fig. 3 is a diagrammatic circuit arrangement of a carrier telephone system of one channel, preferably employing inverted voice frequencies for purposes of secrecy; and Fig. 4 is a similar representation of a multiplex system according to the invention.

In Fig. 1, the curve 1 may be assumed to represent a portion of a varying direct current signal. If a current of this character is applied to a rapidly operating commutator the current for a certain interval indicated by the distance between two adjacent vertical lines is permitted to flow to the line with the line terminals connected in a certain manner to the signaling circuit through the commutator, whereas for the succeeding interval the connection of the line terminals is reversed by the commutator, and so on. As a result the character of the current impressed on the line is somewhat as indicated by the curve 2. This curve is drawn by reproducing portions of the curve of Fig. 1 included between adjacent vertical lines, reversing every alternate portion. It will be observed that the curve 2 has sharp angular portions at the point where the reversal occurs. As is well known, these sharp angles represent, so far as the effect of the current upon a selective circuit is concerned, a number of components having frequencies much higher than the frequency of alternation. If a filter is placed between the commutator and the line, arranged to suppress currents having frequencies higher than a frequency exceeding the frequency of alternation by the frequency range representing the signal, the frequency components represented by these angular portions of the curve 2 are prevented from reaching the line and as a result the actual line current has a form somewhat as indicated by the curve 3. By using a filter having the proper transmission and suppres-

sion properties, the range of frequencies transmitted may be confined to a definite band as is common practice in multiplex carrier current systems.

5 The curve 4 of Fig. 2 may be assumed to represent a portion of an alternating current signal wave and if this wave is commutated at a rate indicated by the closeness of the vertical light lines, a wave of the form indicated by curve 5 will be obtained. This curve has properties similar to the curve representing the output current of a carrier suppression modulator such as is common in the art. In other words, the wave produced 10 by commutating an alternating current represents a pure modulated wave containing frequency components of both side bands but having no component of the carrier frequency itself. By passing the commutated 15 current through a suitable filter, a smooth current such as indicated by curve 6 is obtained. If current of the character represented by curve 5 or curve 6 is passed through a rectifying detector, a current having a frequency double that of the original 20 signaling current represented by curve 4 will be obtained. In order to receive the signal from a wave of the type shown by curve 5 or curve 6 by rectifying the wave with a 25 crystal or tube detector, it is necessary to supply at the receiver a wave of the frequency of alternation, that is, a wave of the original carrier frequency. However, a reversing commutator running in synchronism 30 with the modulating commutator will restore a wave such as shown by curve 5 or 6 to substantially the form of the signal wave indicated by curve 4.

35 Referring to Fig. 3, a system is shown 40 having telephone stations indicated at I and II. Each station may comprise the usual local battery telephone set including the microphone M, receiver R, and may also be provided with a ringer S and a hand generator G. The stations I and II may be connected by local lines L¹ and L² to a toll line 45 ML. The toll line or main line ML terminates at each end in frequency converting apparatus comprising the commutators 10 and 50 12, respectively, and filters, the purpose of which will be described.

The commutators 10 and 12 are duplicates 55 of each other and may have any convenient or suitable design and are assumed to be driven in synchronism and in phase with each other. No means for driving the commutators or for securing synchronism between them has been shown since arrangements for controlling distantly situated 60 commutators in this manner are well known in the art. Furthermore, individual lines such as the line ML may not be concerned in transmission of the synchronizing or control or driving currents since it is sufficient to 65 have at each terminal station a single syn-

chronously driven shaft from which a large number of commutators employed, it may be, by a corresponding number of lines terminating at that station are driven. In such case the control currents for the commutators may be transmitted over a separate circuit or may be superposed on one of the lines as is known in the art.

In operation assuming that communicating 70 relation exists between the stations I and II, and that both receivers are removed from their switchhooks, voice currents originating in the station I pass through the filter LF¹ to one pair of brushes on the commutator 10. The filter LF¹ is designed to 75 pass freely essential voice frequencies but to suppress transmission of frequencies that are very much higher than those required for speech transmission. In the system being described, the commutators 10 and 12 are preferably driven at such a rate and the 80 number of segments on each is so arranged that the frequency of alternation is substantially the same as or slightly above the 85 highest frequency component of the essential speech frequency range. The resulting 90 commutator wave has therefore a frequency of alternation of say 2000 to 2500 cycles per second and is of the general type indicated 95 by curve 5 rather than of the type indicated by curve 2, since the voice wave applied to the commutator is an alternating current wave of the general form indicated by the 100 curve 4. The filter F¹ in this instance may be a duplicate of the filter LF¹ and is arranged to transmit freely currents of all 105 frequencies up to and including the highest essential voice frequency, but to suppress currents of frequencies higher than this limiting frequency. This and the other filters indicated may each be designed in accordance with the principles set forth in the 110 United States patent to G. A. Campbell, 1,227,113 granted May 22, 1917.

115 It was explained in connection with curves 5 and 6 that these curves represent a wave having frequencies comprising the upper and lower side bands without the carrier frequency component. Since the carrier frequency in the present instance is of the same order as the highest essential voice frequency, these side bands produced by commutator 10 comprise two ranges of frequencies, one of which extends from frequencies near zero up to a value approaching the frequency of alternation, and the other range of which includes frequencies from a value slightly higher than the frequency of alternation up to a frequency practically double the frequency of alternation. Since 120 the filter F¹ transmits only frequencies of the voice range, and since the frequency of alternation is at or near the upper limiting essential voice frequency, it is only the lower of these two ranges of frequencies, that 125 130

- is, frequencies of voice range but of inverted order which will be transmitted to the line ML . These inverted voice frequencies are unintelligible to a high degree when converted directly into sound waves. Due to the attenuating characteristics of the filter F^1 , the commutated current will be smoothed out somewhat as indicated by the curve 6, although the curve is not intended as an exact representation of the wave transmitted through this filter since this filter transmits one side band only, while curve 6 more nearly represents a wave containing both side bands.
- Turning now to the opposite terminal of the line ML , the filter F^2 may be a duplicate of the filter F^1 and the inverted voice frequencies received over the line pass through the filter F^2 to a pair of brushes on the commutator 12. This commutator produces a reverse effect to the modulating action performed by commutator 10, and its action may be understood from referring to Fig. 2 and considering that the commutator 12 inverts every alternate current fragment represented by the curve 5 or 6, the effect of which is to produce a wave of the general form of curve 4. In this inverting action, due largely to interruptions at the edges of the commutator segments, a number of high frequency components will be produced and it is the function of the filter LF^2 which is a duplicate of the filter LF^1 to suppress the transmission of currents having frequencies above the voice range. The restored voice frequencies pass therefore over the line L^2 and are received at substation II.
- Transmission from the station II to station I is accomplished in precisely the same manner as has been described of transmission in the opposite direction. Voice currents received from the line L^2 and the filter LF^2 are commutated at 12 producing side bands of frequencies respectively in and above the essential voice frequency range. The lower of the two side bands is transmitted by the filter F^2 , the line ML , filter F^1 to the commutator 10 where it is commutated to produce speech current which is transmitted by the filter LF^2 and the line L^1 to the station I.
- A system of the character above described possesses a high degree of secrecy and the use of a commutator for modulating purposes permits the same degree of secrecy to be obtained by the comparatively simple circuit arrangements that have been described so far that could be obtained only by considerably more complicated apparatus if a modulator of the vacuum tube type for example were employed. The reason for this is that the commutator 10 produces the two side bands without at the same time transmitting double frequencies or unmodified voice frequencies, or unmodulated car-
- rier components, some or all of which would be transmitted by a vacuum tube modulator and would need to be eliminated by additional circuit elements. The currents actually transmitted over the line ML are not understandable if received by an ordinary telephone receiver or if rectified by the usual rectifying detector, and can only be made to produce understandable speech by being commutated or by being received in a rectifying detector to which a wave of the carrier frequency is simultaneously applied. Ringing currents are transmitted in a manner entirely similar to that described of the voice currents from either generator G to actuate the ringers S .
- In Fig. 4, the line ML^2 is shown terminating at each end in two sets of apparatus for enabling simultaneous transmission over the line of two carrier telephone conversations between the pairs of stations III, IV and V, VI, and, in addition, connections for a third telephone conversation employing currents of voice frequency transmitted between circuits 15 and 16. The line ML^2 is shown connected at one end to the band filters F^3 and F^5 and to the low pass filter F_1' . The opposite terminal has band filters F^4 and F^6 , respectively duplicates of F^3 and F^5 , and a low pass filter F_2' . The low pass filters F_1' and F_2' may be duplicates of the filters F_1 and F_2 of Fig. 3, and are shown situated between the main line ML^2 and the terminal circuits 15 and 16 respectively which may be assumed to lead to low frequency signaling sets, such as ordinary telephone stations, and also if desired to composited telegraph apparatus. The commutators 17 and 18 may be driven from the same shaft and also the commutators 19 and 20 may be driven from one shaft, but either the number of segments or the driving arrangements are such that the commutators 17 and 19 produce a less number of alternations per second than do the commutators 18 and 20, it being understood that the commutators 17 and 19 run in synchronism with each other, as do also the commutators 18 and 20 with each other. The filters F^3 and F^4 are arranged to transmit a band of frequencies including the frequency components contained in the modulated wave from commutator 17 or 19. The filters F^5 and F^6 are arranged to transmit a band of frequencies different from that transmitted by the filters F^3 and F^4 and including the frequencies involved in the transmission through the channel containing commutators 18 and 20. For example, the filters F^3 and F^4 may be arranged to pass frequencies from about 4000 to 6000 cycles, while the filters F^5 and F^6 may be arranged to transmit frequencies from 7000 to 9000. The commutators 17 and 19 may then be run at such a rate as to have a frequency of alternation of 3800 and the commutators 18 and 20 at 3200.

and 20 may have a rate of alternation of 6800. With this sort of arrangement, it will be seen that the upper side band is transmitted in each case, it being assumed that this side band comprises a range of frequencies from a lower limiting frequency of about 200 cycles higher than the carrier frequency up to about 2200 cycles higher than the carrier frequency. The filters F' , F^s , F^e and F^{10} are designed to pass currents of the essential voice frequencies and to suppress those of higher frequencies.

The operation of the system of Fig. 4 is as follows: Assuming that the commutators and the filters are arranged to employ frequencies above indicated, the switches 21 will be thrown to engage the upper contact and voice currents originating in station III, for example, pass through the transformer T^i and the filter F' , switch 21 to a pair of brushes of the commutator 17. The resulting upper side band of the frequencies produced by the commutator 17 are transmitted through the band filter F^s , but are prevented from transmission through any of the other filters associated with the system except the filter F^e which is selective of these frequencies. These frequencies are transmitted to the commutator 19 and from there through the filter F^s to the telephone set of the station IV. Signals are transmitted from the station IV to the station III in an entirely similar manner, the commutator 19 serving to produce a modulated wave of which the upper side band is selectively transmitted by filters F^e and F^s . The commutator 17 reproduces the voice frequencies, which are transmitted by the filter F' , while the higher components are suppressed. Voice currents originating in the telephone set of the station V are transmitted through the transformer T^s and filter F^s to the commutator 18 which produces a voice modulated wave, the upper side band of which is transmitted by the band filter F^s , line ML^2 and band filter F^e to the rectifying commutator 20. The received voice currents pass through the filter F^{10} to the telephone set of the station VI. Transmission in the opposite direction is accomplished in a similar manner.

If the switches 21 are thrown so as to include the battery 22 in circuit with the low frequency brushes of the commutators, and if the voltage of this battery exceeds the voltage amplitude of the impressed voice waves, it is evident that the wave applied to the commutators will be of the general form indicated by curve 1, in which case the modulated wave produced by the commutator will comprise not only the two side bands, but a certain amount of unmodulated carrier component. If it is desired to transmit the unmodulated carrier component, the filters F^s and F^e , F^s and F^e must, of course, be designed to have a transmission range in-

cluding the frequency of the unmodulated carrier component. Also it is not necessary that the filters F^s , F^e , etc. should suppress one side band, but if desired they may be arranged to transmit all of the components of the modulated wave having to do with the transmission of the signal.

The system arranged as in Fig. 4 is capable of transmitting two carrier telephone conversations without mutual interference, and in addition an ordinary low frequency telephone conversation originating in either of the terminal circuits 15 or 16, and destined for the opposite of these two circuits. By duplication of the apparatus shown other channels may, of course, be provided to any convenient and desired number, it being understood that the commutators of each channel have a rate of alternation different from that of the commutators of any other channel.

If it is desired to have the voice-range channel of the system of Fig. 4 a secret channel, the filters F'_1 and F'_2 may correspond respectively to the filters F_1 and F_2 of Fig. 3, the circuit 15 leading to the commutator 10 and the circuit 16 leading to the commutator 12. These commutators may be driven from the same respective shafts as the other commutators, the number of segments and the driving arrangements being such as to give the required carrier frequency.

It has been described how both speech and ringing currents can be transmitted and received by converting them first into alternating current waves and then back into signaling currents by means of commutators. The invention is not, of course, limited to the transmission of speech and ringing signals in this manner, but the means and method of the invention may be employed in various manners, and for transmitting other kinds of signals, as may be desired.

What is claimed is:

1. The method of carrier telephony comprising commutating voice currents at a frequency high in comparison with the highest essential speech frequencies to produce a voice-modulated carrier wave and filtering the wave to confine the transmitted frequencies within substantially the extreme frequencies of the side bands.

2. The method of carrier telephony comprising commutating voice currents at a frequency high in comparison with the highest essential speech frequencies and selectively transmitting a portion only of the commutated currents.

3. The method of carrier signaling which comprises separately commutating different message currents at different frequencies all of which are high in comparison with the highest frequency component of said message currents to produce side bands from

- each of said message currents, suppressing transmission of one of the resulting side bands produced from each message current, and simultaneously transmitting the remaining side bands over a common path. 5
4. The method of carrier signaling which comprises separately commutating signal currents at different frequencies all of which are high in comparison with the highest frequency component of said signaling currents, transmitting the commutated currents over a common path and separately commutating the transmitted currents at synchronous rates to yield the different signaling currents. 10
5. The method of signaling which comprises producing signaling currents, commutating said currents at a frequency at least as high as the highest signal frequency necessary for intelligible reception of the signals and filtering the commutated currents to restrict the transmitted range to frequency components lower than the frequency of commutation. 20
6. The method of producing one side band of a voice-modulated carrier wave which comprises commutating a voice current at the carrier frequency and suppressing the transmission of all resulting components except those comprised in one side band. 25
7. The method of transmitting speech which comprises commutating a voice current at a sustained frequency, transmitting one side band of the resulting frequency components and suppressing transmission of the other components. 35
8. The method of multiplex carrier wave transmission which comprises commutating each of a plurality of message currents at respectively different frequencies to produce side bands, suppressing transmission of one of the resulting side bands produced from each message current, and transmitting the remaining side bands simultaneously over the same path. 40
9. The method of multiplex carrier wave transmission which comprises commutating each of a plurality of message currents at respectively different frequencies to produce side bands, suppressing one of the resulting side bands produced from each message current, transmitting the remaining side bands simultaneously over the same path and separating the frequencies representing the different messages by filtering. 55
10. The method of secret telephony which comprises commutating speech current at a frequency in the neighborhood of 2000 to 2500 cycles per second, selecting for transmission the lower side band of the resulting frequencies and suppressing the other frequency components from transmission. 60
11. In a signaling system, a source of signaling waves comprising a range of fre-
- quency components, a commutator for converting said waves into waves of higher frequency, a line for transmitting said waves of higher frequency, and a filter between said commutator and line for restricting the frequencies transmitted to a range of frequencies representing the signaling frequencies and having substantially the same extent as the range embraced by said signaling waves. 70
12. A circuit for transmitting signaling waves including two wave filters, at least one of which transmits electrical waves of the signaling frequency, and a commutator connected between said filters having a frequency of commutation at least as high as the upper essential signaling frequencies. 75
13. A circuit including two wave filters one of which transmits frequencies of the essential voice range, and a commutator connected between said filters having a frequency of commutation at least as high as the upper essential speech frequencies. 80
14. In combination, a commutator, circuits for conveying currents to and from said commutator, a voice-frequency filter in one circuit, and a filter for frequencies above the voice range in the other circuit. 85
15. A two-way translating circuit comprising a transmission line, a transmit-receive terminal circuit having means for transmitting current to and receiving current from said line, a current-reversing commutator connected in circuit between said terminal circuit and said line, and a filter in circuit between said commutator and said line. 90
16. In a signaling system, a source of alternating current signal waves, a commutator for producing from the energy of said waves a signal modulated wave for transmission to a distance, whereby the unmodulated carrier wave component of said signal modulated wave is suppressed, and a band filter for suppressing a portion of the modulated current components before transmission to a distance. 95
17. In a signaling system, a source of signaling waves, a commutator for converting the energy of said waves into a signal-modulated wave, and a filter for suppressing one side band of frequencies of said modulated wave and transmitting selectively the remaining side band. 100
18. In a signaling system, a signal transmission line, a plurality of signal-current circuits associated therewith, and commutators connected one in circuit between each such signal-current circuit and said line, said commutators being arranged to have respectively different rates of commutation. 105
19. In a signaling system, a transmission line, a plurality of signal-current circuits associated therewith, commutators connected one in circuit between each such signal-current circuit and said line, said commutators 110

being arranged to have respectively different rates of alternation and a wave filter connected between each commutator and the line.

5 20. A signaling system comprising a multiplex main transmission line cooperating at each end with a plurality of signaling current branches, each of said branches being connected to said main line through a separate commutator, the said commutators at one terminal of said main line having respectively different rates of commutation.

15 21. In a carrier transmission system including a main transmission line having stations, a carrier wave channel comprising a transmitting signaling set at one of said stations on said line and a receiving signaling set at another of said stations on said line, and means comprising a commutator and a 20 wave filter for connecting each of said sets with said line.

25 22. A multiplex signaling station for a line, comprising a uniformly rotating shaft, a plurality of rotating commutators driven from said shaft and arranged to have respectively different current commutating rates, each of said commutators being provided with sets of terminals for respective associated circuits, a different signal circuit 30 connected to one set of terminals of each of said commutators, a plurality of filters connected in common to said line, the opposite sets of terminals of each of said commutators being connected to one of said filters.

35 23. In a signaling system, a circuit carrying signaling currents comprising a range of frequency components, a line, a commutator connected between said circuit and said line

for converting said signaling currents into alternating currents for transmission over 40 said line, said commutator having a frequency of commutation high in comparison with the upper essential signaling frequencies, and a filter connected between the commutator and the line for restricting the frequencies transmitted to the line to a range 45 substantially equal in extent to that embraced by the components of said signaling currents and lying substantially wholly to one side of the frequency of commutation. 50

24. In a signaling system, a circuit carrying signaling currents, a line, a commutator connected between said circuit and said line for converting said signaling currents into alternating currents for transmission over 55 said line, said commutator having a frequency of commutation high in comparison with the highest essential frequency component of said signaling currents, and a filter 60 connected between the commutator and the line for suppressing the transmission of frequencies higher than the frequency of commutation and for selectively transmitting lower frequencies.

65 25. A two-way terminal translating circuit for a carrier channel comprising a commutator, means including said commutator for producing a modulated carrier wave for transmission and means including said commutator for deriving signals from received 70 carrier waves.

In witness whereof, I hereunto subscribe my name this 17th day of December, A. D. 1921.

RALPH V. L. HARTLEY.
